TRAY FOR OPHTHALMIC TEST LENSES

Filed April 2, 1926

2 Sheets-Sheet 2

UNITED STATES PATENT OFFICE.

EDWARD LINDER, OF PHILADELPHIA, PENNSYLVANIA.

TRAY FOR OPHTHALMIC TEST LENSES.

Application filed April 2, 1926. Serial No. 99,419.

This invention relates to trays, and more particularly to a tray which embodies a plurality of recessed and slotted rectangular sections for receiving an ophthalmic test lens in a fixed vertical or angularly disposed position and in such manner as to protect the lenses and facilitate the placement or removal from the tray of any individual test lens.

10 The principal object of the invention is to provide a tray for ophthalmic test lenses, which is designed to accommodate a relatively large number of lenses, each encased in a flanged rim of uniform size, and adapted to be inserted in slots provided therefor in the tray in equally spaced row formation, for the safe, rapid and convenient handling and storing of a large number of test lenses, said trays adapted to be placed 15 in a cabinet or analogous structures designed for receiving a plurality of such trays.

Another object of the invention is to provide an ophthalmic test lens tray comprising a frame of rectangular formation, with a 20 plurality of lens tray sections secured therein, and extended in parallelism between the two opposite ends of the tray frame and said tray sections provided with a plurality of spaced longitudinal troughs. The troughs 25 in each of the tray sections are provided with a plurality of transverse slots of a width substantially equal to the thickness of the metallic rim in which a standard test lens is encased, and the metallic rim is further provided with a laterally extending flange on 30 one side thereof and about the perimeter of the lens, for the engagement of the said flange on the edge portion of a transverse slot in one of said tray sections when the metallic rim containing a test lens is 35 inserted therein.

Another object of the invention is to provide a test lens tray as specified, which is 40 light in weight, durable in construction, compact in design, and particularly adapted to be used for the purpose for which it is designed.

Other objects of the invention will appear in the following detail description, and 45 in the accompanying drawing, wherein:

Figure 1—is a top plan view of the tray.

Figure 2—is a transverse sectional view on the line 2—2 of Figure 1.

Figure 3—is a longitudinal section on the 50 line 3—3 of Figure 1.

Figure 4—is a bottom plan view of the tray partly in section.

Figure 5—is a detail view of a mounted ophthalmic test lens.

Referring more particularly to the drawing, the invention comprises a rectangular frame 10 of inverted L-cross sectional formation with the upper laterally extending flanges 11 turned inwardly. Formed integrally and connecting opposite flanges 11, 60 are a plurality of relatively narrow strips 12 which are spaced to divide the frame 10 into a plurality of rectangular open spaces 13, adapted to receive a plurality of lens tray sections 14 which will be hereinafter 65 described.

The lens tray sections 14 are secured in the open spaces 13, and to said frame 10 by means of a plurality of U-shaped clamping strips 15 which extend along the undersides 70 of the said strips 12, and throughout the length thereof, and clamp the laterally extended side edges of the lens tray section between the under surface of the strips 12 and the spaced parallel edges of the U-shaped 75 clamping strips 15. The clamping strips 15 are secured to the supporting strips 12 by means of suitable machine screws which extend downward for threaded engagement 80 with the clamping strips 15.

The lens tray sections 14 previously referred to, are preferably formed of sheet metal of a suitable gage and are provided with a plurality of spaced depressions or troughs 16 of any suitable shape which extend throughout their lengths. The troughs 16 are further provided with spaced transversely extended lens receiving slots 17 which extend partially into the laterally extending side edges of the tray sections 14. 95

The lens receiving slots 17 are spaced a sufficient distance to provide a supporting surface between each of the slots for engagement by a flanged shoulder 18, provided on a standard ophthalmic test lens 19. The 100 shoulder 18 extends laterally from one face about the circumferential edge of the lens, the latter being surrounded by a metallic rim 20, as illustrated in Figure 5 of the drawing.

The outer laterally extending side edge 21 of the two end trays abut the inner sides of opposite side members of the frame 10, and are secured against the under surface of the flanges 11, by means of a pair of suitable 110

retaining bars 22. The bars 22 have their upper edges spaced from the flanges 11, so as to snugly receive the edges of the tray sections.

5 If it is so desired, the frame 10 comprising the test lens trays may be fitted on a suitable rectangular wooden base, in any convenient and well-known manner, and the bottom surface of said base may be faced 10 with felt or analogous material, so as not to mar the surface of a table or the like, when a tray as described, is placed thereon.

From the foregoing description, taken in connection with the accompanying drawings, it will be readily apparent to those skilled in the art, that I have provided a practical and convenient carrier tray, for the individual reception of a plurality of ophthalmic test lenses which will maintain 20 the lenses in a substantially vertical anti-rattling position, and will space one lens from the other, in a series of parallel rows.

While I have shown and described one practical embodiment of my invention, it is 25 to be understood, that I do not limit myself to the exact construction as set forth, but consider myself at liberty to make such changes and modifications, as fairly fall within the scope of the appended claims.

30 What I claim is:—

1. An ophthalmic test lens tray comprising a supporting frame having a plurality of longitudinally extending spaced openings, a plurality of lens receiving tray sections, 35 means connected to the under face of said frame for securing said sections to said frame and in said openings, and means provided in said sections for receiving and supporting a plurality of ophthalmic test lenses in spaced parallel relation.

2. An ophthalmic test lens supporting tray comprising a rectangular frame having longitudinally extending spaced strips causing spaced longitudinally arranged openings to 45 be formed, a plurality of lens receiving tray sections, means connected to the under face of said frame for securing said sections to the underside of the frame and supporting said sections in said openings, and means 50 provided in said sections for receiving a plurality of ophthalmic test lenses in individually spaced parallel relation.

3. An ophthalmic test lens tray comprising a supporting frame, means for dividing 55 said frame into a plurality of integrally formed sections, means provided on said first named means for supporting a plurality of lens tray sections, a plurality of lens troughs formed in each of said tray sections, and means provided in said troughs for receiving a plurality of ophthalmic test lenses in a fixed transverse position.

4. An ophthalmic test lens supporting tray comprising a rectangular frame having 60 the upper edges thereof angularly formed to

provide laterally and inwardly extending flanges about the inner sides of said frame, means for dividing said frame into a plurality of integrally formed retaining sections, means provided on said first named 70 means for securing a plurality of test lens tray sections thereto, a plurality of lens receiving recesses formed in each of said tray sections, said recesses being disposed in spaced parallelism, and means provided in 75 said recesses for receiving a plurality of ophthalmic test lenses in an angularly disposed transverse position.

5. An ophthalmic test lens supporting tray comprising a rectangular frame having the 80 top edges of its side members bent at right angles to provide inwardly extending flanges, a plurality of spaced supporting strips formed integrally with said flanges and extended between the opposite ends of said frame, said supporting strips forming a plurality of rectangular openings, a plurality of lens supporting sections positioned in said openings from the undersides thereof, means for clamping the laterally extending side 85 edges of said tray sections to the undersides of said supporting strips and inwardly extending flanges on opposite sides of said frame, a plurality of spaced parallel lens troughs provided in each of said tray sections, and means provided in said troughs 90 for receiving a plurality of ophthalmic test lenses in a vertical transverse position.

6. An ophthalmic test lens tray comprising a rectangular frame having the top edges 100 of its vertical side members bent at right angles to provide inwardly extending flanges about the inner sides of said frame, a plurality of spaced supporting strips formed integrally with the flanges and extending between the opposite ends of said frame, said supporting strips providing a plurality of 105 openings, a plurality of lens supporting tray sections positioned in said openings from the underside of said frame, a plurality of U-shaped clamping members attached to said supporting strips for securing the said tray sections in said openings and to said frame, a pair of spaced lens troughs formed in each 110 of said tray sections, means for anchoring the outer laterally extending edges of the two opposite side lens tray sections to the sides of the opposed side members of said frame, and said troughs having a plurality of 115 equally spaced transversely extended slots for receiving a plurality of ophthalmic test lenses in transverse row formation.

7. In an ophthalmic test lens tray, the combination with a frame of rectangular formation with a laterally and inwardly extending marginal flange on its upper edge and provided with a plurality of longitudinally arranged spaced strips causing elongated openings to be formed, of a plurality 125 of tray sections positioned in the openings 130

with their adjacent edge portions engaged with and under the strips, the remote side edges of the side tray sections being engaged under certain portions of the marginal flange, clamping strips and fasteners for securing the adjacent edges of the tray sections to the first strips, means for clamping

said remote edge portions of the side tray sections to the marginal flange, and means provided in the tray sections for receiving a plurality of ophthalmic test lenses in fixed transverse position.

In testimony whereof I affix my signature.

EDWARD LINDER.
